(57) CLAIM

The ornamental design for a hanger clip, as shown and described.

DESCRIPTION

FIG. 1 is a front view of the claimed design of a hanger clip, the opposite side being a mirror image;

FIG. 2 is a side view thereof, the opposite side being a mirror image; and,

FIG. 3 is a perspective view thereof.

The broken lines showing environmental structures in FIG. 3 are for illustrative purposes only and form no part of the claimed design.

1 Claim, 3 Drawing Sheets
